CULINARY TURNER

Richard S. Latham, Chicago, Ill., assignor to Ekco Products Company, Chicago, Ill., a corporation of Illinois

Application February 20, 1958, Serial No. 49,721

Term of patent 14 years

(Cl. D44—29)

Fig. 1 is a front elevational view of a culinary turner showing my new design.

Fig. 2 is a side elevational view thereof.

The dominant features of the design reside in the portions shown in full lines and in the arrangement of apertures as shown.

I claim:

The ornamental design for a culinary turner, as shown and described.
